UNITED STATES PATENT OFFICE.

EDWARD BEVINGTON, OF HAMILTON, OHIO.

AUTOMOBILE-CARRIED SIGNAL MECHANISM.

1,251,625.

Specification of Letters Patent. Patented Jan. 1, 1913.

Application filed September 13, 1912. Serial No. 119,888.

To all whom it may concern:

Be it known that I, EDWARD BEVINGTON, a citizen of the United States, residing at Hamilton, in the county of Butler and State of Ohio, have invented certain new and useful Improvements in Automobile-Carried Signal Mechanism, of which the following is a specification.

The object of my invention is to provide a novel form of signal, adapted to be readily attached to and removed from an automobile, which will be practical and exceedingly useful in operation, and which may be manually operable with a maximum of ease and facility.

Another important object is to provide a signal which may be manufactured at a nominal cost and sold at a very low figure.

Another object is to provide a signal which is simple in design, and whose few parts are not likely to get out of order, and which is, therefore, durable in use.

With these objects in view and others appearing as the specification proceeds and the nature of the invention more fully appears, the invention resides in the novel construction, combination and arrangement of parts of a signal, as will be hereinafter fully described in the specification, summed up in the claims, and illustrated in the drawing.

In the accompanying drawing, forming part of my specification, and in which like reference-characters denote corresponding parts throughout the several views, I have illustrated a form of embodiment of my inventive ideas capable of carrying out the underlying principles thereof. The several figures of the drawing may be briefly described as follows:

0 Figure 1 is a perspective view of my signal adapted to be supported, or attached to an automobile, in a vertical position;

Fig. 2 is a like view of the signal adapted to be supported, or attached to an automobile, in a horizontal position;

Fig. 3 is a top plan view of the device of Fig. 2, with the parts moved into the position shown in dotted lines in Fig. 2, and the spring-arm shown in section; and

Fig. 4 is a section on the line 4-4, of Fig. 2.

1 designates a supporting member,—in this instance, a plate, which is preferably and advantageously provided with means

permitting it to be secured to a part of the automobile, within convenient reach of the operator, such means, in this instance, being suitable apertures 2, whereby screws, or the like, may be passed therethrough. The plate is desirably of some material which, though possessing the necessary strength and durability, is, at the same time, inexpensive,—as a suitable metal.

3 designates a suitable signal, which may be a disk, as shown, and, if desired, this disk 35 may be colored, as by being painted red.

This disk-signal 3 is carried by a member having pivotal movement on the plate 1; and, in this instance, is shown carried at the end of a rod 4 suitably pivoted to the plate 1, as by being provided with an angled or bent portion 5 rotatably mounted in bearings carried by the plate 1, these bearings being preferably in the form of tongues 6, 6 desirably integral with the plate 1 and bent 75 or rolled over the bent portion 5 of the rod 4, and, as shown, these bearings are carried by one of the edges of the plate. The bent portion 5 constitutes a rock-shaft.

After passing through the bearings 6, 6, 20 the bent portion 5 of the rod 4 unites with a lever 7, desirably in the form of a rod (as shown) of spring material. The lever may carry, at its otherwise free extremity, a handle 8, for convenient manipulation 35 thereof.

The invention comprehends suitable means for yieldingly locking or holding the movable parts of the mechanism in the full line position shown in the drawing; and, to this end, the plate 1 is, in this instance, provided, along one of its edges, with a flange 9, whose wall in cross section (see Fig. 4) may be straight with an inward-bent edge at its top. In operation, to bring the movable parts into the dotted line position shown in Fig. 2, the operator pulls, or presses upward on, the lever 7, which, being of spring material, flexes inward and springs past the top edge 10 of the flange 9, which 100 had theretofore held said lever in the position shown in full lines in Fig. 2; whereupon the rod 4 with the signal-disk 3 drops to the position shown in Fig. 2. A reverse movement of said parts will bring them 105 into the position shown in full lines in Fig. 2, the lever 7 springing past the top edge 10 of the flange 9 and onto the plate 1, bear-

ing forcibly against the inner surface of the flange 9, so that said lever is yieldingly held in the full line position shown in Fig. 2.

While I have, for the purposes of the patent statutes, disclosed in concrete form an illustratory embodiment of my inventive ideas, yet I desire it to be understood that all changes and modifications as come within the scope of the appended claims constitute no departure from the spirit and purview of the invention.

Having thus fully described my invention, what I claim as new and desire to secure by Letters Patent of the United States is:

1. In signal-mechanism adapted to be carried by an automobile, a supporting plate having a flange, and a rod of spring material having an angled portion rotatably carried by said plate, a portion of said rod springing under said flange when the rod is moved to the limit of its movement in one

direction, whereby said rod is yieldingly retained in position, said rod also having a portion constituting a lever.

2. In signal mechanism adapted to be carried by an automobile, a rod adapted to carry a signal and having an angled portion, constituting a rock-shaft, a supporting plate having bearings in which said angled portion is rotatably mounted, a member, of spring material, united to said rock-shaft for rocking the same, and a flange carried by said supporting-plate for yieldingly locking said member of spring material at the limit of its range of movement in one direction.

In testimony whereof, I affix my signature in the presence of two witnesses.

EDWARD BEVINGTON.

Witnesses:

WALLER S. ZACHARY,
RAYMOND H. BROCKER.
